COMBINED CLOCK AND PICTURE STAND

Leslie N. Pollard, 2050 S. Garnsey,
Santa Ana, Calif. 92707

Filed Mar. 30, 1972, Ser. No. 239,856

Term of patent 14 years

Int. Cl. D10—01

U.S. Cl. D42—7 H

FIG.1

FIG.5

FIG.2

FIG.6

FIG.3

FIG.4

FIG. 1 is a front elevational view of a combined clock and picture stand showing my new design;

FIG. 2 is a rear elevation view thereof;

FIG. 3 is a top plan view thereof;

FIG. 4 is a bottom plan view thereof;

FIG. 5 is a left side elevational view thereof;

FIG. 6 is a right side elevational view thereof.

I claim:

The ornamental design for a combined clock and picture stand, substantially as shown and described.
